(57) CLAIM

The ornamental design for a plush toy with a chest article, as shown as described above.

DESCRIPTION

FIG. 1 is a front view of a plush toy with chest article
embodying my invention;

FIG. 2 is a back view thereof;

FIG. 3 is a left side view thereof;

FIG. 4 is a right side view thereof;

FIG. 5 is a top view thereof; and,

FIG. 6 is a bottom view thereof.

The broken line showing of the remainder of the plush toy is for illustrative purposes only and forms no part of the claimed design. The unshown regions of the plush toy form no part of the claimed design.
